UNITED STATES PATENT OFFICE.

ALEXANDER JOZSY, OF NEW YORK, N. Y.

COMBINED TRUNK AND WARDROBE.

1,126,479.

Specification of Letters Patent.

Patented Jan. 26, 1915.

Application filed April 3, 1914. Serial No. 829,285.

To all whom it may concern:

Be it known that I, ALEXANDER JOZSY, a subject of the King of Hungary, and resident of the city of New York, in the county of New York and State of New York, have invented certain new and useful Improvements in Combined Trunks and Wardrobes, of which the following is a specification.

The present invention relates to convertible trunks and wardrobes, its main object being to provide a trunk which may be used for ordinary traveling purposes and which, when occasion requires, can be easily and conveniently converted so as to serve as a wardrobe.

Another object of the invention is to provide a wardrobe trunk which can be manufactured on a commercial scale, or in other words one that is not so difficult to produce as to be beyond the reasonable cost of such an article.

With these and other objects in view, which will more fully appear as the nature of the invention is better understood, the same consists in the combination, arrangement and construction of parts hereinafter fully described, pointed out in the appended claim and illustrated in the accompanying drawings, it being understood that many changes may be made in the size and proportion of the several parts and details of construction within the scope of the appended claim without departing from the spirit or sacrificing any of the advantages of the invention.

One of the many possible embodiments of the invention is illustrated in the accompanying drawings, in which:

Figure 1 is a perspective view of the trunk; Fig. 2 is a similar view showing the device converted into a wardrobe; Fig. 3 is a section taken on line 3-3 of Fig. 1; Fig. 4 is a section taken on line 4-4 of Fig. 3; Fig. 5 is a plan view of a detail of construction; and Fig. 6 is a section taken through a detail of construction.

In the drawings, the numeral 10 indicates the bottom of the trunk, to which are rigidly fastened an end 11, a side 12 and a side 13. Each of these sides is made of two sections, of which the larger ones, denoted by the numerals 14, are attached to the bottom 10, while the smaller ones, in the form of strips 15, are hinged at 16 to the sections 14, and are adapted to be folded onto the latter sections, as clearly shown in Fig. 3 of

the drawings. The end 17 of the trunk is attached to a leaf 18, that is slidably disposed in guides 19, the latter being carried by the sides of the trunk in parallel relation to the bottom 10. To insure a proper motion of the leaf 18 relative to the bottom of the trunk and to support the end 17 in a proper manner, when the trunk is extended to form a wardrobe, the sides 12 and 13 of the trunk are provided with guides 20, in the form of channel-irons, in each of which is slidably disposed a guide rod 21, preferably made of two interconnected sections 22 and 23, the section 22 carrying at that end, which is near the end 17 of the trunk, a spring 24 having a lug 25 which is adapted to engage an aperture 26 in the respective channel-iron 20, thereby holding the leaf 18 and the end 17 in proper position when the said leaf is telescoped into the trunk.

To the section 14 of the side 13 of the trunk is hinged at 27 a leaf 28, said leaf being folded onto the side 13 when the device is converted into a trunk (Figs. 3 and 4), but is adapted to be swung around its hinges to form a continuation of the side 13, when the device is extended to form a wardrobe (Fig. 2). To the end 17 of the trunk is attached a spring 29, which carries a lug 30, that is adapted to enter a socket in the free edge of the leaf 28 when the trunk is extended to form a wardrobe (Fig. 6). A push button 31, also attached to the spring 29, serves to facilitate the disengagement of the lug 30 from said socket. To the section 14 of the side 12 is hinged at 32 a leaf 33, that is folded onto the side 12, as clearly shown in Fig. 3 of the drawings, when the furniture is collapsed in the form of a trunk, but is adapted to swing around its hinges to form a continuation of said side (Fig. 2), a spring 29 and a lug 30 being provided to co-operate with the leaf 33 in the same manner as the similar elements co-operate with the leaf 28.

To the leaf 33 is hinged at 34 a cover 35, to which, in turn, is hinged at 36 a leaf 37. The leaf 37 is normally folded onto the cover 35, but is adapted to swing around its hinges to form a continuation of said cover (Fig. 2). A catch 38, carried by the leaf 37, is adapted to engage a socket in the cover 35 when the said two elements are in their extended positions, thereby holding said leaf and cover in such positions. To the

leaf 37 is furthermore pivotally attached a retainer 39, having an arc-shaped slot 40 in engagement with a lug 41, that is pivotally attached to the end 11 of the trunk. To hold the leaves 28 and 33 in their closed positions, there are provided in the said leaves and in the end 11 of the trunk sockets 42 and 43, respectively, in which are adapted to be seated fingers 44 and 45, respectively, of clamps 46, the said clamps carrying screw bolts 47 in parallel relation to said fingers, said screw bolts being adapted to be passed through openings in the end 11 of the trunk and to be engaged by wing nuts 48. It is obvious that, when the said fingers are seated in their sockets and the nuts 48 are properly screwed up, the leaves 28 and 33 will be held in closed positions relative to their sides 13 and 12, respectively.

The bottom 10, end 11, leaves 28 and 33 and the cover of the trunk are provided with strengthening strips 49 and with suitable corner shields 50 for the well known purpose. Rollers 51 are carried by the end 11 and the bottom 10 of the trunk to facilitate its transportation. Upon the leaf 28 is mounted a lock 52 and upon the cover of the trunk a hasp 53, forming the fastening or locking means of the trunk. The section 15 of the slide 13 of the trunk carries a lock 54, which is adapted to coöperate with a keeper 55 upon the leaf 37 of the cover 35, said two elements forming the fastening means of the furniture when converted into a wardrobe. In the upper edge of the end of the trunk are formed recesses 56, in which are adapted to be seated pins of an extension piece 57, said extension piece serving to give the furniture a better support when extended into a wardrobe. In the latter case a head molding 58 is attached to the end 17 of the trunk. For this purpose in the upper edge of said end are formed recesses 59, into which fit dowel pins upon said molding. In parallel relation to the end 17 of the trunk is carried a bar 60, upon which is adapted to be hung a plurality of garment hangers, 61, etc.

The operation of this device is as follows: When the furniture is in the form of a trunk, the leaf 18, with the end 17 carried thereby, is telescoped into the body of the trunk. The clamps 46 are engaged in a manner above described with the leaves 28 and 33 and the end 11 of the trunk. The lugs 25 upon the springs 24 are seated in the apertures 26 in the guides 20, thereby preventing the end 17 from being drawn out from the body of the trunk. The leaf 37 is folded back upon the cover 35, and the retainer 39 engaged with the lug 41. When in trunk form, the sections 15 of the sides are folded back upon the said sides, the extensions 57 and the head molding 58 being disposed below the side sections 15 in parallel

relation to the sides of the trunk. To convert the trunk into a wardrobe, first the clamps 46 are removed from the trunk and the latter turned in a manner that the end 11 forms the bottom of the wardrobe into 70 which the trunk is to be converted. The lugs 25 upon the springs 24 are then disengaged from the corresponding apertures 26 in the guides 20, and the end 17 with the leaf 18 drawn out from the trunk until the 75 said leaf forms a continuation of the bottom 10. The sections 15 of the sides of the trunk are shifted around their hinges until they are disposed in the planes of the sections 14 of said sides. The leaf 28 is then 80 swung around its hinges until its free end contacts with the end 17, in which position the lug 30 springs into the socket in the said leaf. The retainer 39 is then disengaged from the lug 41 and the leaf 33 with the cover and the leaf 37 hinged to the latter turned around the hinges 32 until the corresponding lug 30 is seated in the socket in the leaf 33. After this the leaf 37 is 85 swung around the hinges 36 and the catch 38 engaged with the socket in the cover 35, the latter with the leaf 37 forming then the door of the wardrobe. The lug 41 is then 90 engaged with the retainer 39, to limit the motion of the door upon the wardrobe. The extension piece 57 and the head molding 58 are then put in place, the garment hangers 61 placed upon the bar 60, and the shelf boards 62 put upon supports 63, which are 95 attached in horizontal positions to the sides 100 of the trunk. To convert the wardrobe, obviously the reverse operations are necessary.

It is to be observed that, in converting the trunk into a wardrobe, the leaves 28 and 33 are reversed with the result that 105 the strengthening strips 49 and the corner shields 50 are concealed from view. It is to be noted that, while herein specific means have been described for locking the leaves 28 and 33 in position when the furniture is 110 in both of its forms, any other suitable mechanisms may be made use of without departing from the invention.

What I claim is:—

In a wardrobe trunk, the combination 115 with a bottom, of an end and two sides rigidly attached thereto, a leaf slidably arranged in parallel relation to said bottom adapted to form a continuation of said bottom, an end rigidly attached to said leaf, 120 means for holding said end in position relative to said bottom when said leaf is telescoped into the trunk, a leaf hinged to one of said sides folded thereonto but adapted to be swung to form a continuation thereof, 125 a second leaf in a similar manner hinged to the other one of said sides, a cover hinged to said last named leaf, a leaf hinged to said cover adapted to be folded thereonto 130 and suited to be swung around its hinges to 135

form a continuation of said cover, means for fixing said last named leaf upon said cover when in the plane of the latter, and means for holding in position the leaves which are hinged to said sides when folded thereonto.

Signed at New York, in the county of

New York, and State of New York, this 18th day of March, A. D. 1914.

ALEXANDER JOZSY.
